SPRING COUNTERBALANCE

Walter H. Haupt, Ludlow, Ky., assignor to The Kelley-Koett Manufacturing Company, Inc., Covington, Ky., a corporation of Ohio

Application July 16, 1937, Serial No. 154,047

8 Claims. (Cl. 248—123)

This invention relates to a counterbalancing system for X-ray apparatus, ultra-violet lamps, and the like.

Among the objects of this invention is the provision of such a system in which weights are substituted by springs. Ordinarily a weight and a spring are regarded as mechanical equivalents and no invention is deemed to reside in their interchange. It has long been desired however, to replace the heavy weights necessary to balance heavy shockproof X-ray heads which contain transformers and oil and frequently weigh over a hundred pounds. The problem is not merely to balance such a head at a given point on a column or standard but to balance it statically at any point on the column while making the head easy to move and balance throughout the height of the column. If such an arrangement is successful, the saving in weight can be utilized to make the column and base stiffer and stronger. The entire saving in weight of course, need not be nullified by making the rest of the apparatus heavier.

It is well known that helical springs do not require equal work to make them contract or expand equal distances at all times. The more the spring is already compressed, the greater the relative amount of work necessary to make it still shorter. The more it is already stretched, the greater the relative amount of work to make it stretch still further. If such a spring is used in a balancing arrangement to act upon a constant weight, there will be more or less cable to take up, depending upon the leverage exerted by the weight. The means provided for taking up and paying out cable while changing the leverage thereupon are an essential part of my invention.

In the drawing, Fig. 1 is a vertical section of an X-ray standard showing the spring and take-up arrangement.

Fig. 2 is a plan view of the top of the column showing the pulley arrangement.

Fig. 3 is a cross section of the column taken along the line 3—3 of Fig. 1.

Fig. 4 is a plan view of the spiral pulley as seen from below.

In the drawing, 10 is the base of the apparatus while 11 is the column. 12 is the X-ray head and carriage (shown only in part) to be balanced. 13 It encircles the column. A cable 13 extends from carriage 12 over a pulley 14 mounted obliquely as shown in Fig. 2 on the top of the column, which is a cap 15.

Within the column 11, there is a spring assembly 16, which is made up of an upper end

plate 17 and a lower end plate 18 between which and into which are mounted a plurality of helical springs 19. If desired, only one spring may be used, but in the case where heavy weights have to be balanced, a plurality is recommended because many small springs are cheaper than one large one and by leaving off one or adding one a closer approximation of the weight to the spring tension can be had. Failure of one spring also will not allow the weight to fall if a plurality of springs are used.

On bottom end plate 18, a second cable 13a, is attached in a non-slidable manner by means of a central eye bolt 20 and then the cable continues down the column, as will be explained. The upper end plate 17 which is stationary during the counterbalancing operation, is adjustable for height, and consequently for spring tension by a vertical screw 21. Turning a nut 22 which is integral with the screw and located above cap 15 is sufficient to accomplish the adjustment since the screw is threaded in plate 17 but unthreaded where it passed thru cap 15. A spring guide 23 is also provided in the column to keep the springs from twisting when the tension is increased by turning nut 22.

Inverted on the upper part of base 10 and within it is a pulley 24 of peculiar shape. It is so mounted as to be freely rotatable on an axle boss 25 which is attached rigidly to the inner side of base 10. The upper end of the pulley is grooved with sheaves, but is generally cylindrical, but the lower end is grooved with sheaves of a rapidly decreasing spiral form. The distance of this spiral from its axis 25 is proportional to the increase in work performed as the springs 19 are stressed from minimum tension, at which they are when carriage 12 is at its uppermost position on the column, to a position of maximum tension which they occupy when carriage 12 is as far down the column as to be in contact with shoulder 26 of base 10. It is believed that a spiral of such or approximately such quickness is known in mechanics as the "fusee spiral" altho absolutely definite information on this point is not at hand.

Another way of expressing this relation is to say that the product of the spring tension times the axial distance of the acting point on the spiral groove is designed to be a constant and effectively equal to the product of the load being balanced times the radial distance of the effective radius on the cylindrical part of 24.

A third way of expressing this would be to say that as the spring tension increases the pull of

the springs is applied closer to center and becomes less effective as rapidly as the pull increases so as to have a constant effect. This constant effect permits the load to be balanced at rest at any point on the column. When the pull of the springs 19 is greatest, its effective lever arm on the pulley is least, therefore, no greater pull is exerted than when the lever arm is greater but the pulling force less.

10 The upper part of pulley 24 is cylindrical so that cable 13 may have a constant point of application. This cable comes down the column after leaving pulley 14, passes unattached thru the spring assembly and then turns toward pulley 24 after leaving a pulley 27 at the base of the column. It is wrapped around the cylindrical portion of pulley 24 sufficiently to allow full traverse of the carriage 12 on the column. Cable 13 is then anchored at its pulley end to a point on the cylindrical part of pulley 24, as shown in Fig. 4.

15 The second cable, 13a runs from the eyebolt 20 around the pulley 28 at the base of the column, thence to and about the spiral portion of pulley 24. At the top point of the spiral it is anchored as Fig. 4 shows. The arrangement is such that cable 13a reaches the apex of the spiral and spring assembly 16 is stretched to its greatest tension when carriage 12 is at its lowermost point.

20 To operate my counterbalancing system it is merely necessary to lift or depress carriage 12 slightly and to cease applying force when the carriage has attained the desired position. 25 Downward motion of the carriage pulls end plate 18 down by exerting a pull on cable 13 wrapped on pulley 24, causing the pulley to rotate and wrap up the cable with a continuously decreasing lever arm. The action may be likened to that of a bicycle going up hill, the drive sprocket continually decreasing in size as the hill grows steeper so that the effort required to turn the pedals stays constant. Lifting the carriage merely reverses the process.

30 I claim as my invention—

1. In an apparatus comprising a column and a carriage to be counterbalanced on said column and a base supporting said column and carriage, a plurality of helical springs vertically arranged 35 inside the column, a pair of end plates to which the ends of said springs are attached, the lower part of the assembly being movable, a combination pulley comprising a spirally grooved portion and a coaxial cylindrical portion, said pulley 40 being rotatably mounted on the base, a cable connecting the lower end of the spring assembly with the spiral groove of the said pulley and a second cable connecting the carriage to the cylindrical part of said pulley, the spiral grooves on the face of the pulley being adapted to guide the second cable so as to keep the counterbalancing force of the spring assembly exerted upon the carriage through said first cable, a constant.

2. In an apparatus comprising a column and a carriage to be counterbalanced on said column, a hollow base supporting said column and carriage, a plurality of helical springs vertically arranged within said column, a pair of end plates to which said springs are attached, the lower part of the assembly being vertically movable within the column, screw means for vertically adjusting the height of the upper one of said plates, a combination pulley comprising a spirally grooved portion and a coaxial cylindrical portion, said pulley being rotatably mounted on the

base, a cable connecting the lower end of the spring assembly with the spiral groove of the said pulley and a second cable connecting the carriage to the cylindrical part of said pulley, the spiral grooves on the face of the pulley being adapted to guide the second cable so as to keep the counterbalancing force of the spring assembly exerted upon the carriage through said first cable, a constant.

3. An apparatus according to claim 2 in which the construction of the spiral pulley is such that as the tension of the springs increase, the effective lever arm of the cable on the pulley, by which the pull of the springs is exerted, becomes less in the same proportion.

4. In an X-ray standard or the like, a base, a column arising from said base, a carriage movable on said column, a plurality of helical springs within said column, end plates to which said springs are anchored, the lower part of the assembly being vertically movable within the column, means for holding rigid the upper one of said end plates, a pulley at the top of said column, pair of pulleys at the bottom of said column, a spiral pulley in said base, a cylindrical portion on said pulley, a cable extending from the said carriage over the first pulley unattachedly down said column, around one of said lower pulleys thence to and about the cylindrical part of said spiral pulley, where it is fastened, a second cable attached to and extending about said spiral pulley back to the other of the pulleys at the base of said column and thence to the lower end plate where it is tightly fastened.

5. An apparatus according to claim 4 in which the spiral pulley has grooves which run in a "fusee" spiral.

6. In an X-ray apparatus or the like, a hollow base, a column arising therefrom, a carriage movable on said column, a plurality of helical springs vertically arranged within said column, a pair of end plates to which the ends of said springs are attached, the lower part of the assembly being vertically movable within the column, a cap on said column, a screw running thru said cap and the upper one of said end plates, a pulley mounted on said cap, a pair of pulleys at the base of said column, an inverted spiral pulley rotatably mounted within the base, said pulley having a cylindrical section, and a cable extending from said carriage over said first pulley down the column, around one of said pulleys at the base of said column, then to and about the cylindrical section of said spiral pulley, a second cable extending about a spiral path on said pulley thence around the second of the pulleys at the base of said column and finally being attached to the lower one of said end plates.

7. An apparatus according to claim 6 in which the spiral path of said spiral pulley is at such distances from the axis of rotation of said pulley that the product of the spring tension times the axial distance of the acting point on the spiral is a constant effectively equal to the product of the load being balanced times the radial distance of the effective radius on the cylindrical part of said pulley.

8. In a counterweight balancing device, a vertical column, a carriage movable along said column, a pulley having combined cylindrical and spirally grooved co-axial portions, a cable joining said pulley and carriage so as to effect a rotary movement of the said pulley as a consequence of the movement of the carriage caused by a pull on the cable which is joined to the

cylindrical portion of said pulley, a helical spring assembly within said column, said assembly comprising an upper rigidly held plate, a lower vertically movable plate and a plurality of helical springs each attached by one of its ends to one of said plates, a second cable joining the lower one of said plates with the spiral portion of said pulley, the proportions of the pulley cable and

spring being such in relation to each other that when the spring assembly is stretched to its maximum by reason of a position of said carriage, the lever arm of the second cable on the pulley, tending to produce rotation thereof, is at 5 its maximum.
